(57) **CLAIM**

The ornamental design for a barbecue grilling tool, as shown and described.

DESCRIPTION

FIG. 1 is a perspective view of an opened barbecue grilling tool showing my new design;

FIG. 2 is a top plan view thereof;

FIG. 3 is a right side view thereof;

FIG. 4 is a rear elevational view thereof; and,

FIG. 5 is a front elevational view thereof.

The bottom view is a mirror image of the top plan view illustrated in FIG. 2, the side not illustrated identical to the side illustrated in FIG. 3 and the broken line showings of a handle form no part of the claimed design.
